UNITED STATES PATENT OFFICE

130,062

DESIGN FOR AN ELECTRIC BLASTING FUSE IGNITER

Robert T. Burgess, Holden, W. Va.

Application June 23, 1941, Serial No. 101,622

Term of patent 14 years

To all whom it may concern:

Be it known that I, Robert T. Burgess, a citizen of the United States, residing at Holden, in the county of Logan and State of West Virginia, have invented a new, original, and ornamental Design for an Electric Blasting Fuse Igniter, of which the following is a specification, reference being had to the accompanying drawing, forming a part thereof, and wherein

Figure 1 is a perspective view of an electric blasting fuse igniter, showing my new design, the jaws thereof being opened;

Figure 2 is a view similar to Figure 1, the tool

being turned over and the view taken on the opposite side thereof;

Figure 3 is a top plan view;

Figure 4 is a side elevational view;

Figure 5 is an end elevational view, looking towards the left of Figure 4;

Figure 6 is an end elevational view, looking towards the right of Figure 4.

I claim:

The ornamental design for an electric blasting fuse igniter, as shown.

ROBERT T. BURGESS.
